ELECTRON GUN

Vladimir K. Zworykin, Philadelphia, Pa., assignor
to Radio Corporation of America, a corpora-
tion of Delaware

Application November 28, 1940, Serial No. 367,606

6 Claims. (Cl. 250—162)

This invention relates to an electron gun and particularly to an electron gun which employs an ultra high frequency generator and ultra high frequency potentials, derived from the generator, for accelerating the electrons as they pass along a linear path.

Electron guns create beams of electrons which are accelerated as they pass along a path toward the object on which they are directed. The electron acceleration may be affected by steady potentials or by varying or alternating currents of proper phase. As electron velocities are increased, it becomes more difficult to supply direct currents.

The present invention has for one of its objects the provision of means for establishing an electron beam of high velocity. Another object is to provide means for generating ultra high frequency currents and for applying forces derived from said currents to accelerate an electron beam. Another object is to provide means whereby ultra high frequency waves may be established with a resonant cavity provided with electron accelerating sections for establishing a high velocity electron beam.

The invention will be described by referring to the accompanying drawing in which Figure 1 is a sectional view and schematic circuit diagram of one embodiment of the invention; Figure 2 is a sectional view along line II—II; and Figure 3 is a sectional view along line III—III.

Referring to Fig. 1, a fluted cathode C, grids G, GG, and resonant cavity member 1 are arranged within an evacuated envelope 3. The cavity member may also act as the envelope. The cavity walls are extended adjacent the grids and cathode to form anodes A, AA. An auxiliary grid 2 may be used to phase the electrons leaving an auxiliary cathode E. In addition to the extensions for the anodes, fins 5 are alternately extended from the cavity walls to support a plurality of apertured members A1, A2, A3, A4, A5 to AN. The apertures in these members are preferably coaxially arranged within the resonant cavity so that they are aligned with a projection E on the cathode. The relative lengths of the several apertures are important and will be described hereinafter.

The cathode is energized in any suitable manner and is connected to the grids G, GG through biasing batteries 7, 9, respectively. The resonant cavity 1 is connected through an anode battery 11 to the cathode. The portion 13 of the cavity beyond the last apertured member AN may

include the elements of an electron microscope, or any object to be bombarded by electrons.

The apertures in the members A1 to AN are of lengths L, L3, L4, L5, and LN, respectively. These lengths are such that an electron entering one of the apertures, with the maximum possible velocity leaves it a half period later, where a half period equals half the period of oscillation of the resonant cavity.

The operation of the device is as follows: The grids G, GG are coupled capacitatively to the anodes A, AA, respectively, and are biased so that electron current to the anodes is suppressed except when the latter have a potential, relative to the cathode, less than the applied D. C. potential. In this manner, electron movements transfer energy from the D. C. supply to create and maintain standing wave oscillations in the resonant cavity. By way of example, with an applied D. C. potential of 15,000 volts, an oscillatory voltage of about 13,000 volts amplitude may be established in the standing waves in the cavity.

An electron beam, weaker than the anode current, will proceed from the cathode projection E along the axis of the cavity passing through the apertures A1 to AN. The electrons of this beam will be accelerated through twice the voltage amplitude of the standing wave oscillation in passing from one aperture to the next. In the first aperture A1, this will be 15,000 volts plus 13,000 volts or 28,000 volts, and in the subsequent stages it will be as follows: A2=28,000+26,000=54,000 volts; A3=54,000+26,000=80,000 volts; A4=80,000+26,000=106,000 volts; and A5=106,000+26,000=132,000 volts. The final aperture AN may be of lesser length.

The lengths may be determined from the equation $\lambda \cdot v / 2c$, where λ is the wave length, v the velocity of the electron, and c the velocity of light. Thus, it may be shown that for $\lambda=40$ centimeters, L1=.16λ=6.2 cms; L2=.21λ=8.6 cms; L3=.25λ=10.0 cms; L4=.28λ=11.2 cms; and L5=.30λ=12.1 cms. These lengths may be varied to obtain the maximum acceleration if the phase variations along the length deviate in practice from the theoretical. Assuming 10% efficiency an output of one milliampere at 100,000 volts would require an input of one kilowatt or a mean anode current of 70 milliamperes, which can be obtained with a cathode including flutings of about 0.15 centimeter in width and 2 centimeters in aggregate length.

Thus, the invention has been described as an

electron gun in which a relatively low D. C. potential is converted into an oscillatory potential. The oscillatory potential appears along a resonant cavity as a function of the standing waves established therein. These potentials are applied to members containing coaxially aligned apertures so that the electrons of a beam passing therethrough are accelerated as they pass from one aperture to the next succeeding one. The apertures are arranged with increasing lengths to phase properly the electrons so that the energy delivered to them increases the electron velocity. The device may be used as the electron gun of an electron microscope, cathode ray tube, or in any device in which high voltage electrons are required.

I claim as my invention:

1. In an electron gun, a member including a resonant cavity, cathode, grid and anode electrodes arranged within said cavity, means including said cavity and said electrodes for converting direct currents into oscillatory standing wave potentials appearing within said resonant cavity, members including apertures arranged along the axis of said cavity and connected thereto so that said potentials are applied to said apertures, and means including said cathode for directing an electron beam through said apertures so that the oscillatory potentials of said apertures increase the velocity of the electrons passing therethrough.

2. In an electron gun, a member including a resonant cavity, a fluted cathode, anode electrodes arranged on either side of said cathode, grid electrodes intermediate said cathode and anodes, said cathode, anodes and grids being located at one end of said cavity, means including said cavity and said electrodes for converting direct currents into oscillatory standing wave potentials appearing within said resonant cavity, members including apertures arranged along the axis of said cavity and connected thereto so that said potentials are applied to said apertures, and means including said cathode for directing an electron beam through said apertures so that the oscillatory potentials of said apertures increase the velocity of the electrons passing therethrough.

3. In an electron gun, a member including a resonant cavity, cathode, grid and anode electrodes arranged within said cavity, means including said cavity and said electrodes for converting direct currents into oscillatory standing wave potentials appearing within said resonant cavity, members including apertures arranged along the axis of said cavity and connected

thereto so that said potentials are applied to said apertures, said apertures increasing in length as the distance from the cathode increases, and means including said cathode for directing an electron beam through said apertures so that the oscillatory potentials of said apertures increase the velocity of the electrons passing therethrough.

4. In an electron gun, a member including a resonant cavity, cathode, grid and anode electrodes arranged within said cavity, means including said cavity and said electrodes for converting direct currents into oscillatory currents appearing as standing waves in said cavity, a plurality of members including apertures located substantially on the axis of said cavity and connected thereto, and means including said cathode for directing a beam of electrons through said apertures so that oscillatory potentials corresponding to said waves deliver energy to increase the velocity of the electrons of said beam.

5. In an electron gun, a resonant cavity member, a pair of anode electrodes forming a part of said cavity member and disposed opposite each other at one end thereof, a cathode positioned between said anodes and spaced therefrom, a pair of grid electrodes located, respectively, between said cathode and anodes, said cathode including an electron emissive portion oriented for the emission of an electron beam along the axis of said cavity, and a plurality of apertured members connected alternately to the walls of said cavity along longitudinal lines, respectively, passing through the junction of the anodes and said cavity, said apertures being coaxially aligned along said axis.

6. In an electron gun, a resonant cavity member, a pair of anode electrodes forming a part of said cavity member and disposed opposite each other at one end thereof, a fluted cathode positioned between said anodes and spaced therefrom, a pair of grid electrodes located, respectively, between said cathode and anodes, said cathode including an electron emissive portion on the surface remote from said anodes and adjacent said cavity for the emission of an electron beam along the axis of said cavity, and a plurality of apertured members connected alternately to the walls of said cavity along longitudinal lines respectively passing through the junction of the anodes and said cavity, said apertures being coaxially aligned along said axis, the lengths of said apertures increasing as the distance from said cathode increases up to the final aperture.

VLADIMIR K. ZWORYKIN.
